TOOL

Percy E. Brooks, Wood-Ridge, N. J., assignor to
 Western Electric Company, Incorporated, New
 York, N. Y., a corporation of New York

Application March 10, 1944, Serial No. 525,881

8 Claims. (Cl. 164—118)

This invention relates to tools, and more particularly to variable material working tools.

An object of the invention is to provide a material working tool, particularly of the punch type, which is simple in structure, highly variable and readily assembled.

With this and other objects in view, the invention comprises a material working element having a plurality of working portions, a body adapted to receive the element in a selected one of a plurality of positions, and a unit adapted to secure the element to the body in any selected one of the positions.

Other objects and advantages will be apparent from the following detailed description when considered in conjunction with the accompanying drawings, wherein

Fig. 1 is a front elevational view of the tool illustrating one of a plurality of arrangements of the parts of the structure, and

Fig. 2 is an end elevational view of the tool, portions thereof being shown in cross-section.

Referring now to the drawings, attention is first directed to the material working elements identified by reference numerals 10 and 11. In the present illustration these elements are substantially identical except that they vary in width and also in the contour of their material working ends. The element 10 has material working ends 14 and 15 of the contours or widths shown in Fig. 2. It will be noted that the material working end 15 is equivalent to the full width of the element 10, while the material working end 14 is considerably smaller in width. The element 11 has material working ends 16 and 17, the ends 16 being, in the present instance, substantially twice the width of the material working end 14, while the material working end 17 is slightly smaller in width than the material working end 15 of the element 10. Otherwise, the elements 10 and 11 have similar features in that their lengths are identical and they are each provided with lateral grooves 19 and 20.

A holder for the material working elements includes a body 25 with an integral shank 26 adjacent the center thereof and extending vertically therefrom for mounting in a ram 27 of a press (not shown). It should be understood that the ram 27 may be a part of the conventional type of punch press, which includes also a work support for a die which may be associated with this structure. A locating member 30 secured to or formed integral with the body 25, extends the full length thereof and is disposed adjacent one edge of the body, as illustrated in Fig. 2. A T-shaped

slot 31 extends the full length of the member 30 as shown. A surface 32 of the member 30 and an adjacent surface 33 of the body 25 form locating portions for the elements 10 and 11 or other elements of similar structures but with varying material engaging ends.

Units, indicated generally at 35, perform two functions, one being to secure any selected material working element in any one of the plurality of positions to the body 25 and to also serve as a stripping means to strip the material, indicated at 36, from the element. There are shown two units 35 in the present embodiment. It should be understood that any desired number of these units 15 may be employed, there being provided in the tool holding means for receiving three of these units. The units include members 38 having square heads 39 selectively receivable in any of a plurality of T-shaped slots 40 in the body 25. The lower ends of the members 38 are reduced, as at 41, and have annular grooves 42 therein. Threads 43 are provided on the members 38 adjacent the reduced ends 41, to receive nuts 44 and washers 45. Clamping elements 46, of the contours shown, are apertured, as at 47, to receive their respective members 38 and have reduced inner portions including tapered or cam surfaces 48 which are receivable in any of the grooves 19 and 20. Convexed or rounded portions 49 are positioned to engage the under surface of the body 25 adjacent T-shaped slots 40, and to rock thereon to force the material working elements, being clamped into position, into intimate engagement with the surfaces 32 and 33. This is brought about through the driving of the nuts 44 on the threaded portions 43 of the members 38. The angular relationship of the surfaces 48, and those of the grooves 19 or 20 which they engage, with respect to the surfaces 32 and 33 during the movement of the element 46 about its fulcrum 49 causes the elements 10 and 11 to be forced into intimate engagement with the surfaces 32 and 33.

A material stripping unit 50 is removably mounted upon the reduced portion 41 of each of the units 35, as illustrated in Fig. 2. The units 50 include head portions 51 centrally apertured, at 52, to receive the reduced portions 41 and threadedly apertured for set screws 53 adapted for interengagement with their respective annular grooves 42. Sleeves 54 are mounted adjacent the corners of the head portion 51 and have interconnecting pins 55 carried by a material engaging pad or plate 56. Threaded lower ends (not shown) of the pins 55 may be disposed in threaded apertures 55 in the pad 56 to complete the connection therebe-

tween. Enlarged portions or heads (not shown) of the upper ends of the pins are receivable in suitable apertures in the head portions 51 to complete the connection therebetween. Compression springs 57, disposed concentric with the sleeves and pins, normally urge their respective plates 56 downwardly fixed distances to serve in stripping the material 36 from the element 10.

Units 60, substantially identical in structure to the units 50, are provided for mounting on the member 30. These units include members 61 having square heads 62 receivable in the T-shaped slot 31 and threaded shank portions for receiving nuts 63 and washers 64 for securing the members, and thus the units, at any desired position with respect to the member 30. Reduced shank portions 65 of the members 61 have annular grooves 66 therein adapted to receive the inner ends of set screws 67 of head portions 68 of their respective units. A pressure pad or plate 69 is connected to the head portion 68 through interconnected pins 70 and sleeves 71, about which are disposed compression springs 72 to normally urge the pressure pad 69 into general alignment with the pressure pad 56. It will be apparent that an inner edge 73 of the head portion 68 of each unit 60 lies in a plane with the surface 32 to assist in supporting its respective element 10 or 11 when forced into place by its respective unit 35.

In preparing the variable tool for operation, one or more of the material working elements 10 or 11 or other elements similar in structure but of varying widths and/or varying contours of the material working ends, may be selected to be secured to the body 25. In the present embodiment only two sizes of material working elements with four different contours of material working surfaces are illustrated and are mounted at spaced positions. Due to the fact that two material working elements 10 and 11 are mounted in the body 25 through the aid of their units 35, two units 60 are employed and are located through longitudinal adjustment of their members 61 in the T-shaped slot 31 for location adjacent their respective material working elements. If desired, either one of these material working elements may be mounted singly in the body 25, and if such should be the case, it would be preferred that this element be mounted adjacent the center of the structure. The unit 35 selected for mounting the chosen material working element would be connected to the body 25 through the central T-shaped slot 40. In this instance one of the units 60 would be employed and would be located adjacent the center of the structure, to assist in supporting the material working element and to cooperate with the unit 50 in stripping the material from the chosen material working end of the element.

It is apparent that with this structure a companion die or work support is necessary and that there exists a relative movement between this structure and the companion die to complete the operation upon the material. It is believed, however, that such additional structure is not necessary for a complete and clear understanding of the invention. Furthermore, numerous figures could be added to the drawings to illustrate the numerous variations which might exist in the width of the material working elements and the contours of their material working ends, but such is not believed necessary to teach the scope of the invention.

Although specific embodiments of the invention

have been shown and described, it will be understood that they are but illustrative and that various modifications may be made therein without departing from the scope and spirit of this invention as defined by the appended claims.

What is claimed is:

1. A variable tool comprising an element having material working ends, a support therefor having surfaces lying in transverse planes, a unit adapted to secure the element to the support by forcing either material working end into intimate engagement with the surfaces, a material stripping unit, and means to secure the material stripping unit to the securing unit.
- 10 2. A variable tool comprising a material working element, a support therefor having surfaces lying in transverse planes, a unit adapted to secure the element to the support by forcing it into intimate engagement with the said surfaces, and material stripping units mounted upon different sides of the element.
- 15 3. A variable tool comprising a material working element, a support therefor having surfaces lying in transverse planes, a unit adapted to secure the element to the support by forcing it into intimate engagement with the said surfaces, a material stripping unit supported by the clamping unit at one side of the element, and another stripping unit carried by the support at another side of the element.
- 20 4. A variable tool comprising an element having material working ends, a support having a plurality of mounting positions, means adapted for connection with the support at any one of the positions to selectively secure the element to the support adjacent thereto, a material stripping unit, and means adapted to secure the stripping unit to the support at any one of a plurality of positions relative thereto and to the element.
- 25 5. A variable tool comprising material working elements, a support therefor having a plurality of mounting positions, means adapted for connection with the support at selected numbers of the said positions to secure the elements to the support adjacent thereto, material stripping units, and means adapted to secure the stripping units to the supports at variable positions adjacent the elements.
- 30 6. A variable tool comprising an element having opposed material working ends and clamp engaging portions therefor, a support therefor having surfaces lying in transverse planes, a clamp adapted for interengagement with the element at either of the said portions, and means carried by the support for moving the clamp relative thereto to force the element into intimate engagement with the said surfaces.
- 35 7. A variable tool comprising an element having opposing material working surfaces of varied contours and clamp engaging portions therefor, a support therefor having surfaces lying in transverse planes, a clamp adapted for interengagement with the element at either of the said portions, and means carried by the support for moving the clamp relative thereto to force the element into intimate engagement with the said surfaces.
- 40 8. A variable tool comprising a punch element having material working ends of varied contours, a support therefor having surfaces lying in transverse planes, and a unit adapted to secure the element to the support by forcing either material working end into intimate engagement with the surfaces.

PERCY E. BROOKS.
